(57) CLAIM

The ornamental design for a fragrance bottle, substantially as shown and described.

DESCRIPTION

FIG. 1 is a top, front and right side perspective view of our new design for a fragrance bottle;

FIG. 2 is a front elevation view of the fragrance bottle shown in FIG. 1;

FIG. 3 is a right side elevation view of the fragrance bottle shown in FIG. 1, the left side view being a mirror image thereof;

FIG. 4 is a rear elevation view of the fragrance bottle shown in FIG. 1;

FIG. 5 is a top plan view of the fragrance bottle shown in FIG. 1;

FIG. 6 is a bottom plan view of the fragrance bottle shown in FIG. 1;

FIG. 7 is a top, front and right side perspective view of a second embodiment of our new design for a fragrance bottle;

FIG. 8 is a front elevation view of the fragrance bottle shown in FIG. 7;

FIG. 9 is a right side elevation view of the fragrance bottle shown in FIG. 7, the left side view being a mirror image thereof;

FIG. 10 is a rear elevation view of the fragrance bottle shown in FIG. 7;

FIG. 11 is a top plan view of the fragrance bottle shown in FIG. 7; and,

FIG. 12 is bottom plan view of the fragrance bottle shown in FIG. 7.
